Patented May 11, 1915.

UNITED STATES PATENT OFFICE.

HUGH H. McGOVERN, OF OAK GROVE, OREGON.

ORE-SEPARATOR.

1,139,206.

Specification of Letters Patent.

Patented May 11, 1915.

application filed July 8, 1914. Serial No. 849,776.

To all whom it may concern:

Be it known that I, HUGH H. McGOVERN, a citizen of the United States, residing at Oak Grove, in the county of Clackamas and 5 State of Oregon, have invented certain new and useful Improvements in Ore-Separators, of which the following is a specification, reference being had to the accompanying drawings.

10 This invention relates to certain improvements in ore separators and has relation more particularly to a device of this general character of a centrifugal type and an object of the invention is to provide a device 15 of this general character having novel and improved means whereby the ore will be operated upon in a thorough and effective manner to assure a maximum of results.

Furthermore, it is an object of this invention to provide a novel and improved device of this general character including a plurality of members mounted for rotation around a common axis and wherein such members are capable of adjustment one 25 relatively to the other.

The invention consists in the details of construction and in the combination and arrangement of the several parts whereby certain important advantages are attained 30 and the device is rendered simpler, less expensive and otherwise more convenient and advantageous for use, all as will be herein-after more fully set forth.

The novel features of the invention will 35 be carefully defined in the appended claims.

In order that my invention may be the better understood, I will now proceed to describe the same with reference to the accompanying drawings, wherein—

40 Figure 1 is a longitudinal vertical section taken through an ore separator constructed in accordance with an embodiment of my invention; and Fig. 2 is an enlarged fragmentary vertical sectional view illustrating in detail the separating members or bowls. Fig. 3 is a fragmentary sectional view illustrating in detail certain features 45 of the invention as herein embodied.

As disclosed in the accompanying drawings, 1 denotes a suitable foundation, from which is directed upwardly a suitable bearing 2, in which is rotatably mounted the shaft 3, adapted for rotation around a ver-

tical axis and suitably secured to the upper extremity of the shaft 3, is a disk 4, of 55 predetermined dimensions and with which is adapted to co-act the adjustable driving disk 5, driven in any manner which will best suit the requirements of practice. By this means, it will be readily perceived that 60 the rotation of the disk 4 may be controlled as best suits the purpose.

Suitably secured to the upper surface of the disk 4 is the flared extremity 6 of the outer separating member or bowl 7, the 65 upper or enlarged end whereof being provided with the outwardly disposed flange 8, whereby an inner separating member or bowl 9 may be adjustably supported relatively to the member 7. The member 9 is 70 insertible within the member 7 and has its lower end terminating in close proximity to the upper face of the disk 4, while the opposite extremity projects above the upper end of the member 7 and is provided 75 with an outwardly disposed flange 10 adapted to overlie the flange 8, so that said flanges 8 and 10 may have co-acting therewith the threaded members 11 adapted to be engaged by the conventional nuts or burs 12, whereby 80 it will be readily perceived that the inner member or bowl 9 may be adjusted relatively to the outer member or bowl 7, with convenience and facility. It is also to be observed that the inner member or bowl 9 85 is of such a transverse diameter relatively to the member 7 as to afford therebetween a passage-way P.

In practice, I find it of advantage to have each of the members 7 and 9 circular in 90 cross section and to the lower end of the inner member or bowl 9, I suitably secure the annular flat ring or member 14 which projects inwardly thereof and which lies in close proximity to the disk 4.

The inner face of each of the members or bowls 7 and 9 is provided with a textile lining 15 preferably carpet, secured thereto only at the lower end and as herein disclosed, through the medium of an annular member or hub 16. Projecting upwardly from the foundation 1, are the uprights or standards 17 which suitably support a hopper 18 directed within the inner member or bowl 9 and provided with a depending discharge chute 19 terminating in

close proximity to the disk 4. The ore or pulp to be operated upon is delivered with in the hopper 18, from a conveyer 20, traveling thereacross and supported in a conventional manner and is discharged through the chute 19, within the bowls 7 and 9 and it will be readily perceived that the resultant centrifugal action created by the rotation of the members or bowls 7 and 9, 10 will cause the ore or pulp to travel upwardly of the bowls, during which time the metal to be separated therefrom will be collected or concentrated upon the lining 15 and the tailings discharged over the 15 upper edges of the members or bowls 7 and 9 and as herein disclosed such tailings are received within a housing surrounding the upper portions of the members or bowls 7 and 9 and provided with a downwardly inclined outlet chute 21 through which the tailings are adapted to be discharged.

As the particular form of conveyer 20 forms no part of my present invention, other than its coaction with the bowls 7 and 9, it is not believed that a detailed description thereof is necessary, other than to state that I find in practice to have such conveyer comprise a plurality of spaced rods 22, in such spaced relation as to prevent the passage therethrough of particles over three-eighths of an inch in diameter. I also find it of advantage in practice to dispose intermediate the conveyer 20 and the upper ends of the bowls 7 and 9 the screen 23 which may be of any ordinary or preferred construction. I also find it of advantage to have terminating a predetermined distance above the conveyer 20, so as to discharge thereover and through the screen 23, with 35 in the bowls 7 and 9, a conduit 24, leading from any suitable source of water supply.

In operation it will be perceived that the ore to be separated is delivered from the conveyer 20 into the hopper 18 from which it is discharged upon the disk 4 and the resultant centrifugal action due to the rotation of the disk 4 will cause the ore to travel over the inner surfaces of the bowls 7 and 9, the metal adhering to the carpets 45 15 while the tailings are discharged over the upper edges of the bowls 7 and 9 and collected within the surrounding housing and from which said tailings are discharged through the chute 21. By this arrangement it will be seen that the ore to be separated is sub-divided and each portion sent over a single collecting surface.

From the foregoing description, it is thought to be obvious that an ore separator constructed in accordance with my invention is of an extremely simple and comparatively inexpensive nature and is particularly well adapted for use by reason of the convenience and facility with which it may be assembled, and it will also be obvious

that my invention is susceptible of some change and modification without material departure from the principles and spirit thereof, and for this reason I do not wish to be understood as limiting myself to the 70 precise arrangement and formation of the several parts herein shown in carrying out my invention in practice.

Having thus described this invention, what I claim is:—

1. A centrifugal ore separator comprising a body mounted for axial rotation, a bowl secured to said body, and a second bowl nested within the first mentioned bowl and separated therefrom, the bottom of said inner bowl being substantially open, each of said bowls being provided with a surface adapted to retain values, said bowls being relatively so positioned as to sub-divide the pulp and each adapted to separately concentrate its respective portion, and means coacting with the upper extremities of the bowls for maintaining the inner bowl in operative position.

2. A centrifugal ore separator comprising a body mounted for axial rotation, a bowl secured to said body, and a second bowl nested within the first mentioned bowl and separated therefrom, the bottom of said inner bowl being substantially open, each of said bowls being provided with a surface adapted to retain values, said bowls being relatively so positioned as to sub-divide the pulp and each adapted to separately concentrate its respective portion, and adjustable means connecting the upper extremities of the bowls whereby the inner bowl is maintained in operative position.

3. A centrifugal ore separator comprising a body mounted for axial rotation, a bowl secured to said body, and a second bowl nested within the first mentioned bowl and separated therefrom, the bottom of said inner bowl being substantially open, each of said bowls being provided with a surface adapted to retain values, said bowls being relatively so positioned as to sub-divide the pulp and each adapted to separately concentrate its respective portion, the upper extremities of said bowls being provided with overlying flanges, and means coacting with said flanges for maintaining the inner bowl in operative position.

4. A centrifugal ore separator comprising a body mounted for axial rotation, a bowl secured to said body, and a second bowl nested within the first mentioned bowl and separated therefrom, the bottom of said inner bowl being substantially open, each of said bowls being provided with a surface adapted to retain values, said bowls being relatively so positioned as to sub-divide the pulp and each adapted to separately concentrate its respective portion, the upper extremities of said bowls being provided with

overlying flanges, and adjustable means co-acting with said flanges for maintaining the inner bowl in operative position.

5. A centrifugal ore separator comprising a plurality of nested bowl members maintained in spaced relation, the bottom of the inner bowl being substantially open, each of said bowls being provided with a surface adapted to retain values, said bowls being

relatively so positioned as to sub-divide the 10 pulp and each adapted to separately concentrate its respective portion.

In testimony whereof I hereunto affix my signature in the presence of two witnesses.

HUGH H. McGOVERN.
